FOLDABLE EXERCISING BICYCLE

Carl W. Rubel, 2402 State Highway 20,
Marysville, Calif. 95901

Filed June 13, 1969, Ser. No. 17,690

Term of patent 14 years

Int. Cl. D21—03

U.S. Cl. D34—5

Des. 216,903

PAGE 2

FIGURE 1 is a top plan view of a foldable exercising bicycle, showing my new design;

FIGURE 2 is a side elevational view, the opposite side being substantially similar in appearance;

FIGURE 3 is a rear elevational view; and,

FIGURE 4 is a front elevational view.

I claim:

The ornamental design for a foldable exercising bicycle, as shown and described.
